UNITED STATES PATENT OFFICE.

JAMES L. BREESE, JR., OF WASHINGTON, DISTRICT OF COLUMBIA.

VACUUM-FUEL-FEED DEVICE FOR INTERNAL-COMBUSTION ENGINES.

1,293,683.

Specification of Letters Patent.

Patented Feb. 11, 1919.

Application filed June 14, 1918. Serial No. 240,066.

To all whom it may concern:

Be it known that I, JAMES L. BREESE, Jr., a citizen of the United States, residing at Washington, District of Columbia, have invented certain new and useful Improvements in Vacuum-Fuel-Feed Devices for Internal-Combustion Engines, of which the following is a specification, reference being had to the accompanying drawings, forming a part thereof.

The purpose of this invention is to provide an improved device of the nature of a vacuum fuel feed device for internal combustion engines. The specific purpose of the invention is to provide a more reliable speed to the engine under circumstances of unavoidable change of level of the device with respect to the carbureter, as in aeroplane service. It consists in the elements and features of construction shown and described, as indicated in the claim.

In the drawing:

The figure is a vertical axial section of a vacuum fuel feed device equipped with the features constituting this invention.

The usual features of a vacuum fuel feed device are shown in the drawing, 1 being the reserve fuel chamber, 2 the vacuum chamber suspended within the reserve chamber, 3 the suction connection for producing partial vacuum in the vacuum chamber. 4 which is usually a mere atmospheric connection is in this construction a connection leading to a source of super-atmospheric pressure, represented conventionally by what may be regarded as a compressed air chamber, 4^a. 5 is the valve controlling the suction connection to the vacuum chamber, 6 the valve controlling the pressure connection to the vacuum chamber, 7 the float in the vacuum chamber which, by means of a lever system, 8, operates the valves, 5 and 6, according to the level of liquid in the vacuum chamber. 9 is a pipe line leading from a low level tank, not shown, for supplying liquid fuel to the vacuum chamber, 2. 10 is a check valve which controls the communication of the pipe line, 9, with the vacuum chamber, said check valve being adapted to be seated by pressure within the vacuum chamber, and opened readily by flow of—or to permit flow of—the liquid into the vacuum chamber when the conditions tend to cause such flow. 11 is a check valve which controls the outlet from the vacuum chamber into the reserve chamber,

1, being adapted to be seated by suction or partial vacuum operating in the chamber, 2, and to be opened with and by the flow of the liquid from the vacuum chamber into the reserve chamber as usual. 13 is the connection from the reserve chamber, 1, for supplying the carbureter. It is contemplated that, when it is desired, super-atmospheric pressure may be maintained in the compressed air chamber, 4^a, by any suitable means for that purpose, not shown. Usually a pressure of from one to two pounds will serve the purpose of the device, which is to afford pressure at all times upon the reserve chamber, 1, for supplying the carbureter from said chamber, so that the supply may be maintained either even though it may be found desirable to locate the entire device somewhat below the level of the carbureter, or, in case the conditions of use cause the vacuum feed device to be temporarily at a lower level than the carbureter, as is frequently the case in aeroplane service. Such pressure, it will be seen, would under such circumstances be necessary in order that the carbureter might be supplied in the absence of conditions which would cause it to be supplied by gravity.

It will be seen that the operation of the device is the usual operation of a vacuum fuel feed device of this character with the exception that instead of atmospheric pressure being admitted to the vacuum chamber upon the opening of the valve 6, by the rise of the float, there will be admitted to said chamber pressure somewhat in excess of atmospheric. The presence of this super-atmospheric pressure necessitates the valve, 10,—which would otherwise be unnecessary,—for controlling the communication of the vacuum chamber with the liquid fuel supply line, 9. It will be seen that upon the reversal of the valve situation,—that is, the opening of the suction valve, 5, and the seating of the pressure-controlling valve, 6, the action will be precisely the same as in the usual construction of this class of devices, except that the super-atmospheric pressure existing in the chamber, 2, will cause a little more air to be taken from said chamber by the suction; but this will occur so promptly as not to substantially affect the operation of the device. Also the existence of the super-atmospheric pressure above the valve, 6, will make necessary a little deeper immersion of the float, 7, that is, a little

higher rise of the liquid in the vacuum chamber, 2, for unseating said valve, 6, and seating the suction valve when the vacuum chamber is filled; that is, the vacuum chamber will fill to a somewhat higher level than would be the case if there were only atmospheric pressure instead of super-atmospheric pressure admitted by the valve, 6. These slight variations in the action of the device are practically negligible, but the gain in quickness of emptying of the vacuum chamber into the reserve chamber, and the insuring of supply from the reserve chamber to the carbureter, constitute the substantial advantages sought.

I claim:—

In a vacuum fuel feed device, in combina-

tion with a vacuum chamber and suction connection thereto, a reserve chamber into which the vacuum chamber discharges; a fuel supply line leading to the vacuum chamber; means adapted to obstruct back flow from said vacuum chamber through said supply line; air passages from the tops of the chambers, respectively, a source of super-atmospheric pressure with which both said passages communicate; and means for alternating the dominance in the vacuum chamber of the suction and super-atmospheric pressure.

In testimony whereof, I have hereunto set my hand at Washington, D. C., this 31st day of May, 1918.

JAMES L. BREESE, JR.
